1 Claim. (Cl. 181—27)

This invention relates to contracted horns having minimum reflection of sound at the mouth of the horn and some wall leakage.

In the accompanying drawings FIG. 1 represents a longitudinal section of the device constructed in accordance with my invention and FIG. 2 is a graph showing the output pressure response for a horn embodying the invention.

The embodiment of this invention shown in the drawings will now be described in detail.

The horn 1 of FIG. 1 has innumerable pores or slits in the wall 2, which pores are arranged near the mouth portion as described hereinafter. Air is allowed to leak through the pores or slits and is damped by acoustical resistance 3 such as silk cloth or wire gauze stretched over the pores or slits.

The sound wave travelling from the horn throat 4 is initially a plane wave 5 and gradually changes to a spherical wave 6 as it passes the region where the wall has pores or slits. The change in shape of the sound wave results from the fact that the horn tends to have the character of the open end of an acoustical tube at the portion of the horn having pores owing to the leakage through the wall and the wave at the open end assumes the form of spherical wave as is well known.

Upon reaching the horn mouth 7 the sound wave surface can take the form of a sphere 8 whose radius is almost equal to that of the horn mouth if suitable leakage through the wall is allowed. If the radius of the sound wave at 8 is equal to the radius of the horn mouth 7, the sound wave does not reflect at the horn mouth and the output sound pressure of the horn has no peak nor dip at varying frequencies.

According to the theory explained hereinafter, the necessary mouth radius of the horn to satisfy this condition is just half of that of the usual horn. As is well known, the usual horn with a small mouth radius has a bad frequency characteristic owing to the reflection of the sound wave at the horn mouth which is caused by the difference between the radius of the spherical sound wave at the mouth of the horn and the radius of the horn mouth itself.

On the other hand, if leakage through the mouth portion of the wall of the horn is selected in accordance with this invention, horns or apparatus with relatively small mouths, but with excellent frequency characteristics can be made. The tweeter and squawker horns embodying this invention have wider directional characteristics owing to the relatively smaller horn mouths as compared with conventional ones; while woofer horns embodying this invention have more convenient dimensions and weights for domestic use. For example, the usual woofer horns must have mouth dimension of 2 m. x 2 m. in order to truly reproduce bass tones of 50 cycles per second and to maintain an even frequency characteristic.

2

Further, the so-called horn baffle is also reduced in size for a horn embodying this invention.

The theory of this invention will now be explained briefly with reference to an exponential horn as follows:

Differentiating by time the condensation of the air contained in the increment of volume 9 at the section 11 having a cross-sectional area S and thickness Δx in FIG. 1, and multiplying by ρc^2 we get the sound pressure p :

$$10 \quad \frac{\partial p}{\partial t} = \rho c^2 \cdot \frac{uS - (u + \Delta u)(S + \Delta S) - gp(2\pi R \Delta s)}{S \cdot \Delta x} \quad (1)$$

where

ρ =mean density of air,

c =sound velocity,

15 R =radius of the horn at the section 11,

S =the cross-sectional area of the horn at the section

$$11 = S_0 e^{mx},$$

S_0 =the cross-sectional area at the throat of the horn,

e is the base of natural logarithms,

20 x is the axial distance from the throat to the section 11, m =flaring constant of the horn,

$$\Delta s=\text{length of the arc } 10=\Delta x \sqrt{1+(mR/2)^2}$$

$$(2\pi R \Delta s)=\text{area of the circular band } 10,$$

u =particle velocity of air at the section 11, and

25 gp =particle velocity of air leaking through the pores or slits of the wall.

Now velocity potential ϕ gives sound pressure $p=\rho \partial \phi / \partial t$ and particle velocity $u=\partial \phi / \partial x$ as usual; then Formula 1 leads to equations

$$30 \quad \frac{\partial^2 \phi}{\partial x^2} + m \frac{\partial \phi}{\partial x} + (k^2 - j\omega G) \phi = 0 \quad (2)$$

$$G = 2pg\sqrt{(1/R)^2 + (m/2)^2} \quad (3)$$

35 where $k=\omega/c$, ω =angular frequency of sound and $j=\sqrt{-1}$.

The solution $\phi \propto e^{\lambda x + j\omega t}$ of the Equation 2, when G =constant, is

$$40 \quad \lambda = - \left[\frac{m}{2} + jk\sqrt{1 - \beta^2 - jC^2 G/\omega} \right] \quad (4)$$

where $\beta = \omega c / \omega$ and $\omega c = mc/2$ =cutoff angular frequency of the horn.

45 In the case of the usual tone range ($\omega > \omega c$), $1 - \beta^2 > 0$; therefore, the argument, that is, the angle between a vector and its reference axis, for the function in the root in (4) is negative and acute; then the argument of the root itself is also negative and acute; hence we can put

$$50 \quad \lambda = - \left[\frac{m}{2} + jk(a - bj) \right] \quad (5)$$

where

$$55 \quad \left. \begin{aligned} \sqrt{2}a &= \sqrt{\sqrt{(1 - \beta^2)^2 + (C^2 G/\omega)^2} + (1 - \beta^2)} > 0 \\ \text{and } \sqrt{2}b &= \sqrt{\sqrt{(1 - \beta^2)^2 + (C^2 G/\omega)^2} - (1 - \beta^2)} > 0 \end{aligned} \right\} \quad (6)$$

The acoustical impedance density of this horn is, then,

$$60 \quad Z = p/u = \rho \frac{\partial \phi}{\partial t} / \left(- \frac{\partial \phi}{\partial x} \right) = \rho j \omega \phi / (-\lambda \phi) = \rho C / [a - j(b + \beta)] \quad (7)$$

The output sound wave at the horn mouth is nearly a spherical wave, the radius of which is almost equal to the

radius of the horn mouth; and the impedance density at the mouth is, therefore, nearly equal to

$$Z_s = \rho c / [1 - j / kr] \quad (8)$$

where r = radius of horn mouth; this computation is well known in the acoustical engineering of usual or conventional horns.

The condition for avoiding reflection of the sound wave at the horn mouth is, then,

$$Z = Z_s$$

or

$$a - j(b + \beta) = 1 - j / kr$$

$$\therefore a = 1$$

and

$$b + \beta = 1 / kr$$

referring to Equation 6, then, we can derive the conditional equations

$$r = 1/m \dots \text{(mouth radius)} \quad (9)$$

$$G = m/c \dots \text{(constant)}$$

hence

$$g^{-1} = \rho c \sqrt{1 + (mR/2)^{-2}} \quad (10)$$

The usual horn with a solid wall has an impedance density of $Z' = \rho c / [\sqrt{1 - \beta^2} - j\beta]$, which is well-known and also derivable from the Equation 7 when we substitute $G = 0$ in the Equations 6 and 5; $G = 0$ means that there is no leakage in the wall; the minimum reflection at the horn mouth occurs when $Z' = Z_s$; thence we get $\sqrt{1 - \beta^2} = 1$ and

$$\beta = 1 / kr = 1 / [\omega r / c] = \frac{c}{\omega r}$$

hence

$$r = 2/m \dots$$

(mouth radius of the usual horn) (11)

According to Equation 9, the radius of the horn embodying this invention has a size of $1/m$, which is just half the size of the mouth radius of the usual horn. To obtain a good response from this half-sized horn over its reproducing frequency range, however, the Equation 10 must be satisfied. In Equation 10 g means the acoustical leakage conductance per unit area of the wall and it will be seen that change in g along the horn is almost proportional to the change in R (the radius of the cross section of the horn); hence the area of the wall made up

of the pores or slits is to be nearly proportional to R .

It is desirable that the horn wall have no leakage near its throat, but getting near the mouth, the wall gradually permits sound leakage in accordance with Equation 10, in order to avoid unnecessary loss of sound power; and the leakage conductance must be almost real, that is, purely frictional, rather than inertial or elastic conductance, in order to obtain the desired condition over the reproducing frequency range.

One of the invented hornspeakers, the response of which is observed by a Brüel & Kjaer's apparatus and is shown in FIG. 2, has a mouth area of about 230 cm^2 and approximate low and high cutoff frequencies of 320 c./s. and 3000 c./s. respectively. Its response, which rises 6 db per octave in the lower range owing to the small size of the mouth but has no conspicuous peak nor dip, can easily be compensated by a conventional tone controlling device.

This invention is also applicable to all other shapes of horns such as conical or hyperbolic horns as well as to the exponential horn of the particular example.

What I claim is:

A contracted horn including a wall flaring from a throat to a mouth with a flaring constant m , the radius of the horn at said mouth being equal to approximately $1/m$, the portion of said wall of the horn adjacent said mouth having openings therein and acoustical resistance material covering said openings to provide a varying damped leakage conductance therein of approximately

$$1 / \rho c \sqrt{1 + (mR/2)^{-2}}$$

per unit area at any point along said portion of the wall, in which ρ is the mean density of air, c is the velocity of sound and R is the cross-sectional radius of the horn at said point, thereby to ensure minimum mouth reflection.
